DESIGN FOR A LAMPSTAND OR SIMILAR ARTICLE

Clark F. Galehouse, Manhasset, N. Y., assignor to Arnold Brilhart Ltd., Great Neck, N. Y.

Application April 29, 1946, Serial No. 129,097

Term of patent 3½ years

(Cl. D48—20)

To all whom it may concern:

Be it known that I, Clark F. Galehouse, a citizen of the United States of America, residing at Manhasset, Long Island, in the county of Nassau, State of New York, have invented a new, original, and ornamental Design for a Lampstand or Similar Article, of which the following is a specification, reference being had to the accompanying drawing, forming a part thereof.

The figure is a perspective view of a lampstand showing my new design.

The legs are evenly disposed about the corner of the base.

I claim:

The ornamental design for a lampstand or similar article, as shown.

CLARK F. GALEHOUSE.
